UNITED STATES PATENT OFFICE

RALPH G. JOHNSON, OF ROGERS, ARKANSAS

BARREL LIFT

Application filed December 27, 1928. Serial No. 328,802.

This invention relates to portable barrel lifts. The invention is designed particularly for lifting, transporting and tilting drums containing oils in warehouses where oils are dispensed. The common practice in dispensing the oils is to roll the drums up on to racks, so that their contents may flow out by gravity into the smaller measuring vessels. Owing to the large variety of lubricating oils usually kept in stock, drums containing all of the varieties cannot well be kept on a rack at the same time, and hence a considerable amount of labor is required, and much time is lost, in exchanging the drums on the rack.

By means of the present lift, any drum may be readily picked up from the floor and tilted to allow its contents to flow out, and it may be as readily replaced on the floor, and if desired, it may also be transported to any desired part of the warehouse on the lift. While the lift is useful in handling oil containing drums, it will be obvious, that it may also be used for handling drums or barrels of any description.

In the accompanying drawing,

Fig. 1 is a side elevation of the lift, partly in section, on the line 1—1 of Fig. 2, a barrel being shown mounted upon the lift, in dotted lines;

Fig. 2 is a section on the line 2—2 of Fig. 1;

Fig. 3 is a side elevation of the lift, tilted into position to pick up a barrel;

Fig. 4 is a rear elevation, looking from right to left in Fig. 3, with the barrel removed; and

Fig. 5 is a section on the line 5—5 of Fig. 4.

Referring to the drawing, *a* indicates a stand, constituting the supporting member of the lift, and composed of two triangular side frames 1 and 2, spaced apart and connected together by a suitable number of cross bars 3. The side frames are preferably made of metal tubing. The bases 1^a, 2^a of the triangular frames are adapted to rest upon the floor, and in the apices of the frames, opposite the bases, are provided bearings 4, for a shaft 5, which is held against longitudinal movement in the bearings by cotter

pins 6. A tilting frame 7 is mounted upon the shaft 5 between the members 1 and 2 on the stand, this frame comprising parallel handle bars 7 and 8, connected together by a rod 9 and also by a cradle *c* which is mounted upon the handle bars. The shaft 5 extends through the handle bars near their rear ends and the cradle is also connected to the handle bars at their rear ends and lies about centrally over the shaft 5. This cradle comprises parallel side rails 10, preferably of angle iron, which are connected by downwardly bent cross bars 11. Metal uprights 12, secured at their upper ends to the rails 10 and fastened at their lower ends to the handle bars 7 and 8 by U-bolts 13, support the cradle above the handle bars. The rails 10 are extended beyond the ends of the handle bars, and metal toes 14 extend upwardly at an obtuse angle to the rails. These toes are adapted to engage the bottom of a barrel *d* in the lifting operation. The toes 14 and the rear corners 1^b, 2^b of the frame are approximately equidistant from the shaft 5 which pivots the frame to the stand. For engaging the upper rim of the barrel, a rod 15 is slidably mounted in the cradle, and this rod is provided with a hooked end 15^a, adapted to engage the rim. As shown, two of the cross pieces 11 of the cradle are provided with eyes or bearings 11^a, at their central portions, and the hook-bar 15 slides in these bearings. The rear end of the hook-bar is provided with a stop 15^b, to limit its forward movement.

In the operation of lifting a barrel from the floor, the handle bars 7 and 8 of the lift are raised to a substantially vertical position, with the toes 14 of the cradle resting upon the floor adjacent the bottom of the barrel, and the hook-bar is raised by hand and allowed to drop so that its hook will engage the rim of the barrel. In tilting the handle bars to a position slightly beyond the vertical, as shown in Fig. 3, the device fulcrums upon the toes 14, and the stand *a* swings by gravity toward the rear end of the cradle and its rear bars lie substantially in alignment with the handle bars, while the angle portions 1^b, 2^b of the stand rest upon the floor adja-

cent the toes of the cradle. By slightly rocking the barrel the toes will pass under the lower edges of the barrel. By then rocking the handle bars to the left, in Fig. 3, the 5 whole device will fulcrum on the angle portions 1^b, 2^b the stand and as the handle bars are brought to the horizontal position, the barrel will slide along the inclined faces of the toes, pushing the hook-bar forward, and 10 the stand will rock until its lower or base bars 1^a, 2^a rest upon the floor, as shown in Fig. 1. As the device, with its load, fulcrums on the rear corners of the stand, the stand will not be forced away from the barrel while the 15 barrel is being lifted, as would occur if the stand remained upon its base bars, unless braced by the operator's foot. When the handle bars reach the horizontal position, the tilting frame may be locked against backward rocking movement by a chain 16, which 20 is secured to the central part of the cross-rod 9, on the tilting frame, and which may be hooked to an eye 17 on the forward cross-rod 3^a of the stand.

25 After the handle bars have been brought to the horizontal position and connected to the stand by the chain, the device with the barrel thereon may be moved to any position, by pulling or pushing upon the handle bars, the 30 sides 1^a, 2^a of the stand serving as runners. For moving cans and small barrels indoors on floors which are not very rough, the device will not require rollers; but rollers may be applied to the stand, if desired. When a can 35 or barrel is mounted upon the lift, it will be obvious that it can be tilted to any desired position to empty the contents through the spout 18. It will also be obvious that the barrel can be replaced upon the floor by tilting the handle bars to the upright position 40 and then releasing the hook from the upper edge of the barrel.

What I claim is:

In a barrel lift, a stand, a tilting frame 45 pivotally mounted in the upper part of the stand to rock in a vertical plane, a cradle on the frame above the stand and having toes at its rear end adapted to engage the ground when the frame is in vertical position, and 50 a hook on the cradle adapted to engage the upper rim of a barrel, the distance from said toes to the pivotal axis of the frame being approximately the same as the distance between said axis and the rear lower corner 55 of the stand, whereby the stand will swing toward the cradle and the rear corner only of its base will engage the ground under said point of connection when the frame is tilted on to said toes.

60 In testimony whereof I affix my signature.
RALPH G. JOHNSON.
